UNITED STATES PATENT OFFICE

98,650

DESIGN FOR A TRAILER

Fred E. Kaunitz and Lester R. Kaunitz,
Bay City, Mich.

Application November 12, 1934, Serial No. 53,993

Term of patent 7 years

To all whom it may concern:

Be it known that we, Fred E. Kaunitz and Lester R. Kaunitz, citizens of the United States, residing at Bay City, in the county of Bay and State of Michigan, have invented a certain new, original, and ornamental Design for Trailers, of which the following is a specification, reference being had to the accompanying drawing forming a part thereof.

In the drawing—

Fig. 1 is a side elevation of one side of the trailer showing my new design.

Fig. 2 is a side elevation of the opposite side.

Fig. 3 is a top plan view.

What we claim is:

The ornamental design for a trailer as shown.

FRED E. KAUNITZ.

LESTER R. KAUNITZ.
